(57) **CLAIM**

The ornamental design for an audio and/or video capture device, as shown and described.

DESCRIPTION

FIG. 1 is a front and bottom perspective view of an audio and/or video capture device showing our new design, covered by phone or tablet;

FIG. 2 is a front, rear and bottom perspective view thereof; FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a front and bottom perspective view of an audio and/or video capture device, without phone or tablet;

FIG. 10 is a front, rear and bottom perspective view of FIG. 9;

FIG. 11 is a front elevational view of FIG. 9;

FIG. 12 is a rear elevational view of FIG. 9;

FIG. 13 is a right side elevational view of FIG. 9;

FIG. 14 is a left side elevational view of FIG. 9;

FIG. 15 is a top plan view of FIG. 9;

FIG. 16 is a bottom plan view FIG. 9;

FIG. 17 is a front and bottom perspective view of a second embodiment of an audio and/or video capture device, without phone or tablet;

FIG. 18 is a front, rear and bottom perspective view of FIG. 17;

FIG. 19 is a front elevational view of FIG. 17;

FIG. 20 is a rear elevational view of FIG. 17;

FIG. 21 is a right side elevational view of FIG. 17;

FIG. 22 is a left side elevational view of FIG. 17;

FIG. 23 is a top plan view of FIG. 17; and,

FIG. 24 is a bottom plan view of FIG. 17.

The broken lines environment of phone or tablet in FIGS. 1-8 is for illustration purpose only and forms no part of the claimed design.

1 Claim, 21 Drawing Sheets
